UNITED STATES PATENT OFFICE

2,221,785

MECHANICAL ADJUSTER AND
MANIPULATOR

Leslie Douglas, Nashville, Tenn.

Application August 4, 1938, Serial No. 222,955

4 Claims. (Cl. 128—57)

This invention relates to improvements in mechanical adjustors and manipulators designed for the correction and treatment of certain abnormal conditions of man and animal, but more particularly of man. The instrument is intended to gradually and painlessly correct any and all subluxations, stiffnesses, weaknesses, and adhesions, ligatights and muscular contractions, contractures and tensions of the three hundred articulations of the human body, including those of the spinal column, the costo-vertebral and the sacro-iliac articulations, the knee, arches of the foot, shoulder, and clavicle especially, and for massage and manipulation of tissue and muscle.

One of the objects of my invention is to provide, in a device of this character a roller carrying bodies of rubber or other resilient material of various shapes, especially suited for the purpose intended, and which may be removed from the roller or placed thereon in various advantageous positions and arrangements and securely locked thereon.

Another object of my invention is to provide, in a device of this character, means whereby the weight of the device, and therefore the pressure exerted by it upon a person being treated therewith, may be adjusted to suit the needs of the case, and further that the location of the center of gravity of the device may be adjusted as desired.

A further object of my invention is to provide an instrument of this type which is relatively simple and cheap to manufacture, which is durable and not likely to get out of order and which is simple and easy to use.

With the foregoing and other objects in view, my invention consists of the novel construction, combination and arrangement of parts, as hereinafter more specifically described and illustrated in the accompanying drawing, wherein are shown certain embodiments of the invention, but it is to be understood that changes, variations and modifications can be resorted to which come within the scope of the appended claims.

My invention may be more readily understood by reference to the accompanying drawing in which,

Figure 1 is a horizontal section through a manipulator embodying my invention in its preferred form,

Figures 2, 3 and 5 are elevations showing various arrangements of parts suitable for treating various conditions, and

Figure 4 is an elevation of an alternative form 55 of my invention especially adapted for colonic

massage, and for adjustment of spinous processes, one side of transverse processes, and innominate bones, etc.

Referring now in more detail to the drawing and to Figure 1 in particular, the numeral 10 indicates the tubular core member which is exteriorly threaded for its entire length. Threadedly engaging and closing the ends of the core member 10 are the cap members 11 projecting outwardly from the centers of which are the axle 10 studs 12 upon which are rotatably carried the operating handles 13. The space within the tubular core member 10 between the cap members 11 is occupied by a plurality of removable, cylindrical weights 14 preferably made of lead or other relatively heavy material and a plurality of weight spacing or locating members 15 preferably formed of wood or other relatively light material. It is, of course, understood that while, for purposes of illustration, I have here shown two weights and two weight spacing members as completely filling the space within member 10, these weights and weight spacing members may be made as small and as numerous as desired in order to allow for close adjustment of the weight 25 and the center of gravity of the device. For example, lead shot may be used as weight material if desired.

Carried upon and engaging the exteriorly threaded surface of the tubular core member 10 are the comparatively long interiorly threaded sleeves 16 and the comparatively short interiorly threaded sleeves 17. Sleeves 16 carry the cylindrical bodies of resilient material 18 which may be formed of felt, rubber or other suitable material. I prefer that they be formed of sponge rubber, that they be vulcanized to the external surface of sleeves 16, and that their exposed surfaces be covered by suitable material such as cloth, adhesive tape, felt or the like, 18a. These cylindrical bodies are preferably formed with one square and one bevelled end, the bevelled end being in the form of a frustum of a cone, for purposes which will later appear.

The sleeves 17 carry the cylindrical bodies 19, 45 of similar material as bodies 18, and having their exposed surfaces protected by the cover material 19a similar to cover material 18a. Bodies 19 are of greater diameter than that of bodies 18 but are much shorter in length.

In Figure 4 I have shown another form of resilient body 20. Body 20 is constructed of material and covering similar to bodies 18 and 19 just described but its external surface is that of a toroid. It is designed to be carried upon the 55

tubular core member 10 in the same manner as bodies 18 and 19 just described.

Also carried upon and engaging the exterior threaded surface of the tubular core member 10 are the interiorly threaded locking nuts or rings 21 which are adapted to bear against the ends of sleeves 16 and 17 and to retain or lock said sleeves upon member 10.

Thus it will be seen that by removing one or both caps 11 the bodies 18, 19 and 20 may be removed from core member 10 by rotation relative thereto, the interiorly threaded surface of the sleeves cooperating with the exteriorly threaded surface of member 10. Bodies 18, 19 and 20 may be placed upon core member 10 in any desired order or arrangement and may be adjusted to occupy any desired position thereon and may be locked or retained in their adjusted positions by the lock nuts or rings 21.

Also by adding or removing weights 14 and spacers 15 the total weight of the instrument may be adjusted. By suitably arranging the weights and spacers the center of gravity of the instrument may be shifted toward either end or located in the center of the instrument.

As an example of one of these various arrangements of parts, Figure 2 illustrates their disposal in an arrangement which is especially adapted for use in correcting subluxations of the vertebrae. The distance between the adjacent ends of bodies 19 is adjusted so as to permit the spinous processes of the patient's spinal column to enter between them and so that the peripheral surfaces of bodies 19 bear directly upon the transverse processes of the vertebrae. Since the conditions vary with the size and physical make up of each individual patient it is essential that this adjustment be properly made for each case. If the distance between bodies 19 is too small the spinous processes will not enter properly and will be subject to too much pressure. Also, in the case of certain abnormally formed spinous processes, too little distance between bodies 19 may cause a displacement of the centrum or body of the vertebrae.

If the space between bodies 19 is too great, their peripheral surfaces will fail to bear upon the transverse processes and most of the advantages of the treatment will be lost. Thus it will be seen that this adjustment and the accuracy thereof is very essential to optimum results.

The bodies 18 are adjusted so their square ends abut and support the outer ends of bodies 19 and lock nuts or rings 21 are tightened against sleeves 16 so that all parts are retained in adjustment. The weight of the device is adjusted by adding or removing a sufficient number of weights and filling any remaining space with suitable spacers. If it is desired to exert more force or pressure upon the transverse processes on one side of the spine than upon those on the other side, as for example, in the treatment of certain cases of scoliosis and rotation of the spine, the weight members may be arranged so as to concentrate 65 the weight at one end of the instrument.

The instrument is then applied with a back-and-forth rolling motion to the spine of the patient who occupies a prone position, the peripheral surfaces of bodies 19 gradually and painlessly urging the transverse processes in a direction to correct subluxations of the articulations of the spine. The peripheral surfaces of bodies 18 exerting a similar but less intense pressure upon the ribs and the whole producing a beneficial massaging and stimulative effect upon the

parts. The feelings of the patient are generally used as a guide in judging the amount of pressure to be exerted.

The parts may be arranged as shown in Figure 3 wherein the bodies 19 have been removed and bodies 18 brought together so that the square ends thereof abut in such manner as to form a continuous resilient roller of uniform diameter. This arrangement may be used, either with or without weights as an ordinary massage roller for the correction of adiposity and like conditions. Without weights, it may be used upon the face and neck to stimulate the tissues, etc. It is also useful in strengthening the arches of the foot.

The arrangement illustrated in Figure 4, 15 wherein bodies 18 and 19 have been removed and body 20 substituted therefor may be used, weighted as desired, for massaging the colon, for relieving constipation, adhesions and the like, and for adjustment of spinous processes, one side 20 of transverse processes, and innominate bones, etc.

The arrangement illustrated in Figure 5, wherein the bodies 18 have been placed upon the core with their bevelled ends adjacent and spaced slightly apart, may be used upon certain patients 25 in a manner similar to that described in reference to Figure 1 and may also be used in massaging and strengthening the muscles of the arm, leg and the like.

While I have described the principle of my invention, together with the structures which I now consider the preferred embodiment thereof, it is to be understood that the structures shown are merely illustrative and that such changes may be made, when desired, as fall within the scope of the 35 invention as claimed.

Having thus described my invention what I claim and desire to secure by Letters Patent is:

1. In a device of the class described a roller comprising a tubular core member, cylindrical 40 bodies of resilient material carried concentrically upon said core, and a plurality of weights and a plurality of weight spacing members removably carried within said tubular core.

2. In a device of the class described, a tubular core member externally threaded for its entire length, internally threaded cap members engaging and closing the ends of said tubular core member, an axle carried by each of said caps, a handle rotatably carried upon each of said axles, a plurality of interiorly threaded sleeves surrounding said tubular core member and engaging the threads thereof in such manner that rotation of a sleeve about said tubular core member will change the location of said sleeve in relation to 55 the other sleeves and to the tubular core member, means for locking said sleeves to said tubular core member for preventing such rotation of a sleeve relative to said member, and a plurality of cylindrical bodies of resilient material each surrounding 60 and affixed to one of said sleeves.

3. In a device of the class described, a tubular core member externally threaded for its entire length, internally threaded cap members engaging and closing the ends of said tubular core member, an axle carried by each of said caps, a handle rotatably carried upon each of said axles, a plurality of interiorly threaded sleeves surrounding said tubular core member and engaging the threads thereof in such manner that rotation 70 of a sleeve about said tubular core member will change the location of said sleeve in relation to the other sleeves and to the tubular core member, means for locking said sleeves to said tubular member for preventing such rotation of a sleeve 75.

relative to said member, a plurality of cylindrical bodies of resilient material each surrounding and affixed to one of said sleeves and a plurality of weights and a plurality of weight spacing members removably contained within said tubular member, whereby the weight and the location of the center of gravity of the instrument may be adjusted.

4. A device of the class described consisting of a core member, cylindrical bodies of resilient ma-

terial carried concentrically upon said core member, a plurality of weights of relatively heavy material and a plurality of weight spacing members of relatively light material separately and removably carried by said core member, whereby the weight and the weight distribution of said device may be altered without altering the positions of the resilient bodies.

LESLIE DOUGLAS. 10
